UNITED STATES PATENT OFFICE.

JAMES M. McCausland, of Pepperell, Massachusetts, assignor of one-fourth to Albert McCausland, of same place.

MACHINE FOR COATING PAPER.

SPECIFICATION forming part of Letters Patent No. 399,151, dated March 5, 1889.

Application filed June 22, 1888. Serial No. 277,887. (No model.)

To all whom it may concern:

Be it known that I, JAMES M. McCausland, of Pepperell, in the county of Middlesex, State of Massachusetts, have invented a certain new and useful Improvement in Machines for Coating Paper, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved machine represented as in use, and Fig. 2 a plan view of the same, the belts being removed.

Like letters and figures of reference indicate corresponding parts in the different figures of the drawings.

This invention relates to machines for coating paper on both sides at one operation for use in lithographic and other fine printing.

In the drawings, A represents the frame of the machine, B C the cylinders or rolls, and D the paper. The cylinders B C are preferably about five feet in diameter and are journaled by means of transversely-arranged shafts *x x* in the frame A, about twelve feet distant from each other, said shafts being provided with pulleys *b*, connected by a crossed belt, *d*. The shaft *x* of the cylinder C is also provided with a main driving-pulley, *f*, to which power is transmitted by means of a belt, *g*, leading to the main driving-shaft. (Not shown). At each end of the upper side bars, *h*, of the frame is secured a curved arm or bracket, *i*, which projects over the adjacent cylinder B C at each end thereof.

To each pair of brackets *i* are secured four transversely-arranged straight brushes, *k*, the bristles of which come nearly into contact with the surface of said cylinders.

A transversely-arranged circular brush, *m*, is journaled to each set of brackets *i*, between the outer and second straight brush *k*, as best seen in Fig. 1, the shaft of said brushes being provided with pulleys 15 and connected by a belt, 25, disposed thereon, one of said brushes being also provided with a pulley, 35, from which a belt, 45, leads to a pulley, 46, on a counter-shaft above.

At each end of the lower side bars, 1, of the frame-work A is secured a transversely-arranged trough, *p*, for containing the coating mixture, a feeding roll or cylinder, *q*, being journaled in each of said troughs.

A transversely-arranged circular brush, *r*, is journaled at each end of the upper side bars, *h*, so that the bristles of said brushes respectively come into contact with the surface of the feed-rolls *q* as the brushes revolve. A transversely-arranged guide-roll, *t*, is journaled in the upper frame-bars between each brush *r* and its adjacent cylinder B C in such a manner that its surface nearly touches the ends of the bristles in said brush.

Diagonally and longitudinally arranged coils of steam-pipes *v*, provided with valves *w*, are secured to the frame A by means of brackets *y*, said pipes being connected with any suitable steam-supply. These coils are disposed in an inclined plane which impinges the upper surface of one cylinder and the lower surface of the other and constitute an inclined passage between them, through which the paper passes from one cylinder to the other.

Guide-rolls 2 are journaled in a convenient position above the frame A, and are each provided with a pulley, 55, said pulleys being connected by a belt, 65.

In the use of my improvement the roll of paper, 75, is journaled on a mandrel mounted in the frame A, and the tanks *p* filled with the coating material. Power being applied to the machine, the cylinder C is caused to rotate from right to left and the cylinder B from left to right, the guide-rolls 2 and circular brushes *m r* at the same time being revolved. The paper D is fed from the roll 75 over the right-hand guide-roll *t*, between it and the adjacent coating-brush *r*, which, being in contact with the feed-roll *q* in the trough *p*, receives the coating material from said roll and deposits it upon the outer surface of the paper as it passes. The paper is then passed over the cylinder C and under the brushes *k m*, which spread the coating evenly upon the surface and impart the required finish thereto in the usual manner. Between the cylinders C and B the paper passes between the coils of steam-pipe *v*,

whereby the coating is rapidly dried sufficiently to allow its coated surface to be brought in contact with the cylinder B without injury, the paper being passed under said cylinder and 5 carried upward over the guide-roll *t*, where its opposite surface is coated in substantially the same manner by the revolving brush *r*, adjacent to said roll, said coating being finished, as before, by passing the paper over the cylinder B and under similar distributing-brushes *k m*. After leaving the cylinder B the paper is led over the guide-rolls *z* and into the ordinary drying apparatus. (Not shown.)

It will readily be seen that by passing the 15 paper from the roll 75 directly over the cylinder B the apparatus may be employed for coating paper on one side only, as is sometimes desirable.

I do not confine myself to the system of belting shown for driving the cylinders, rolls, &c., as they may be driven in any suitable manner.

Having thus explained my invention, what I claim is—

25 1. In a machine of the character described, the combination of a frame, two cylinders journaled in said frame, two coils of steam-pipe disposed between said cylinders in an inclined plane, impinging the top surface of 30 one cylinder and the bottom surface of the other cylinder, said coils forming a straight passage between them through which the paper passes to be dried, troughs for containing the coating material, provided with a feed-roll and secured, respectively, at each end of 35 said frame, a coating-brush journaled in said frame in contact with said feed-roll, and a guide-roll for the paper journaled near each of said coating-brushes in such a manner that the 40 paper will receive a coating from said brushes on opposite surfaces as it passes over said rolls and cylinders, substantially as set forth.

2. In a machine of the character described,

the combination of a frame, two cylinders journaled in said frame and revolving in opposite directions, a trough for containing the coating material, provided with a feed-roll and secured at each end of said frame, a revolving coating-brush journaled in each end of said frame in contact with said feed-rolls, 45 50 guide-rolls for the paper journaled, respectively, in said frame nearly in contact with said coating-brushes, a series of laterally-arranged straight brushes and a revolving brush for distributing the coating as the paper passes over said cylinders, and diagonally-arranged coils of steam-pipe for drying the coated surface of the paper as it leaves one cylinder, whereby it is adapted to be brought in contact with the second cylinder to permit 55 60 the opposite surface to be coated, substantially as specified.

3. In a machine of the character described, the combination of the frame A, the revolving cylinders B C, journaled in said frame, 65 brushes for depositing the coating material upon opposite surfaces of the paper as it respectively passes over said cylinders, and the steam-coils *v*, secured between said cylinders for drying the paper as it leaves the cylinder 70 C, and thereby preventing it from adhering to the cylinder B, substantially as set forth.

4. In a machine of the character described, the combination of the frame A, the cylinders B C, journaled in said frame, the troughs *p*, 75 secured to said frame and provided with feed-rolls *q*, the revolving coating-brushes *r*, journaled in said frame, the guide-rolls *t*, the finishing-brushes *k m*, supported above said cylinders, and the steam-pipes *v*, adapted to dry 80 the paper as it passes between the cylinders, substantially as specified.

JAMES M. McCausland.
